RECLINING-CHAIR.

SPECIFICATION forming part of Letters Patent No. 329,272, dated October 27, 1885.

Application filed July 2, 1885. Serial No. 170,519. (No model.)

To all whom it may concern:

Be it known that I, EZRA G. CAMERON, a citizen of the United States, residing at Charlotte, in the county of Eaton and State of Michigan, have invented certain new and useful Improvements in Reclining-Chairs, of which the following is a specification, reference being had therein to the accompanying drawings.

10 My invention relates to improvements in folding or reclining chairs, and is designed to produce a chair that may be reclined at any angle, providing a foot-rest adaptable to the different angles of reclining and extensible, 15 and that may be adapted to use as a bed. As it is not broadly new to produce chairs that may have their backs set at any desired angle and provided with extensible foot-rests, the improvement in this case is confined to the 20 constructions and combinations of parts as set forth in the claims.

In describing the device reference is had to the annexed drawings, in which Figure 1 represents a longitudinal vertical section of 25 the chair; Fig. 2, a rear elevation, partly in section; Fig. 3, a side elevation of the chair adapted to be used as a couch.

The legs A preferably cross, as shown, and are held in position at their lower extremities 30 by cross-pieces B, which also support longitudinal strips C. The seat-frame D is secured to and braces the upper ends of the legs. Pivoted to the rear upper ends of the legs is the back E, consisting of a suitable frame 35 with a series of longitudinal springs, F. Pivoted to the upper front ends of the legs are short uprights G, having pivotal connection to the arms H, which latter also pivotally connect to the back. Thus as the back is 40 reclined the uprights G will move in nearly a parallel direction, while the arms will move nearer the seat, but still remain about parallel thereto. From the back, above the pivotal point thereof, downwardly extend arc 45 ratchet-arms I, one on each side, guided each by an eye, K, in the lower rear portions of the legs, the ratchet-teeth engaging with a pawl consisting of a longitudinally-pivoted strip, L. This strip extends across the space

between the legs and has its pivotal bearings 5c in them. A downwardly-extending portion or arm, M, of the pawl-strip is connected to a spring, N, which acts to keep the pawl in normal engagement with the ratchets. By means of a lever, O, pivoted to one of the 55 uprights G, and a connecting-rod, P, which extends from said lever to the arm M, the pawl may be caused to turn on its pivots, and so disengage with the teeth, thus allowing 60 the back to fall. To raise the back, the arms are grasped and pulled forward and upward. The strips C are slotted longitudinally and form guides for the extensible foot-rest R. The guided support for the said foot-rest consists of strips S, fixed at one end to the said 65 foot-rest, and at the other connected by a rod, T, which passes through the slots in the said strips C. The foot-rest, as well as the chair proper, is supported on casters. By making the guiding portions of the foot-rest to fit 70 rather snugly in ways in which they travel the said foot-rest may be made to retain any position in which it may be placed relative to the chair.

The foot-rest R consists of two sections 75 hinged one to the other. One section, U, carries a wide strip, V, below the top, which forms an inclined foot-rest when the said section is lowered, as shown in dotted lines in Fig. 1, in which position the entire device 80 may be moved under the front of the chair. When elevated, the section U is retained in position by spring-catches W, and, being provided with a broad top strip, X, forms a rest 85 when the chair-back is nearly on a line with the seat and the occupant reclines at full length. In this position the arms are somewhat higher at the front than at the rear, as in Fig. 3.

To adapt the chair to use as a bed, the seat 90 proper has hinged to its front end a supplemental seat-frame, Y, which being extended, and having its free end supported by hooks engaging in eyes in the top of the section U, as shown at Z, Fig. 3, the body of the occupant is supported through the entire length.

In practice various parts of the chair—such as the arms, back, both parts of the seat, and

the foot-rest—are upholstered for the purposes of comfort and ornamentation.

I claim—

1. A chair having an adjustable back, an extensible seat, and an independently-extensible foot-rest, serving the additional function of a support for the seat-extension, substantially as and for the purpose specified.
2. A chair having a reclining-back, ratchet-arms on said back, a pawl normally engaging said arms, pivoted arms connected to said back, an extensible seat, and a foot-rest formed

of two sections hinged together and having guiding-ways in the chair-frame, said foot-rest performing the additional function of a support for the extensible portion of the seat, substantially as and for the purpose specified. 15

In testimony whereof I affix my signature in presence of two witnesses.

EZRA G. CAMERON.
